UNITED STATES PATENT OFFICE

BERNARD A. GEURINK AND LOUIS H. GEURINK, OF EAST CLEVELAND, OHIO

GAS BURNER

Application filed May 16, 1928. Serial No. 278,136.

This invention, as indicated, relates to a gas burner. More particularly it comprises a gas burner providing an enlarged chamber over which is secured a burner plate providing a series of orifices, said orifices being formed in parallel relation with each other and the plate intermediate said orifices being formed in a series of corrugations presenting concave upper surfaces and convex lower surfaces. These corrugations preferably are formed of substantially semi-circular extent and thus provide continuously curved lower surfaces terminating at the respective margins of the orifices. This construction provides for a passageway on the under side permitting the free flow of gas to the orifices, and also provides on the upper side for the admission of an excess amount of air about the base of the orifices so that complete combustion may take place at any pressure of the mixture supplied in the burner. To the accomplishment of the foregoing and related ends, the invention, then, consists of the means hereinafter fully described and particularly pointed out in the claims.

The annexed drawings and the following description set forth in detail certain mechanism embodying the invention, such disclosed means constituting, however, but one of various mechanical forms in which the principle of the invention may be used.

In said annexed drawings:

Fig. 1 is a side elevation of the burner and the adjacent portion of a mixing arm, the burner portion being shown in section; Fig. 2 is a top plan view of the construction shown in Fig. 1; and Fig. 3 is a transverse vertical sectional view taken along the line 3—3, shown in Fig. 1, looking in the direction of the arrows; and Fig. 4 is a transverse sectional view taken along the line 4—4 shown in Fig. 1, looking in the direction of the arrows.

The burner comprises an elongated casing 1 which is preferably made in two sections. The lower section 2 comprises a shallow rectangular receptacle preferably with flanged marginal walls 3 providing a seat 4 for the upper section, and having a depressed portion 5 adjacent one end terminating in a cir-

cular base 6 suitably recessed to engage with a complementary portion on the mixing arm of the burner. The mixing arm 7 is provided adjacent its forward end with an offset lug 8 to provide a base against which a securing bolt 9 may be engaged to serve as a fastening means for the burner and as a pivot about which the burner may be swung. A second fastening bolt 11 is provided adjacent the forward portion of the burner and engages through suitable apertures formed in the top plate and base. An enlargement 12 may be provided on the base at the point where said aperture is formed to provide a seat for the nut 13 on the end of said securing bolt.

The top section 14 is preferably in the form of an inverted shallow receptacle having inclined marginal walls 15 merging with the burner plate 16. The burner plate is provided with a plurality of transverse orifices 17 between which depressions 18, of substantially semi-circular cross-section, are located. On the under side of the burner plate a series of convex transverse surfaces 19 of substantially semi-circular cross-section are positioned between the orifices and present gas passageways having continuously curved lower surfaces terminating at the margins of said respective orifices, and thus a large volume of fuel in a state of agitation is maintained immediately below the respective burner orifices.

The top section 14 is preferably formed with bosses 20, centrally of the depressions 18, between the orifices adjacent the securing bolts providing a reinforcement for the structure at such point, suitable apertures for said bolts being provided centrally of said bosses.

As is clearly shown in Figs. 1, 3 and 4, the top section 14 is adapted to be engaged upon the seat or shoulder 4 formed on the lower section of the burner. The offset flange 21 formed on the marginal walls of the lower section of the burner is spaced from the outer margin of the top plate to permit the insertion of cement or suitable packing 22 between said parts to make the two sections of the burner gas tight.

- The burner is preferably formed by casting and it has been found that it is unnecessary to saw or finish the slots or orifices in any way as they can be formed with sufficient accuracy to serve in the form in which they are originally cast. There is an advantage residing in this circumstance due to the fact that a freshly sawed surface has a tendency to absorb constituents of the gases and cause deposits of various materials to be formed about its edges, whereas a cast surface has a scale which is substantially free from chemical action with respect to the constituents of the fuel.
- As has been indicated, the construction not only lends itself to greater ease of manufacture than other constructions of this character, but through its particular form provides for more effective passage of the gas through the orifices without loss of effective pressure or any snapping back when the flame is burned low.

Increased effectiveness of the burner is also due to the provision on the exterior surface of the burner plate of transverse channels at a level beneath the level of the orifices, within which passageways air may flow so as to supply an ample quantity of oxygen about said orifices in order that complete combustion may take place at substantially every variation of pressure of gas, which may be supplied through said burner.

Other modes of applying the principle of our invention may be employed instead of the one explained, change being made as regards the mechanism herein disclosed, provided the means stated by any of the following claims or the equivalent of such stated means be employed.

We therefore particularly point out and distinctly claim as our invention:—

- An apparatus of the character described having in combination a mixing arm providing a pivot bearing, a gas burner provided adjacent one end with a corresponding pivot bearing, and mounted on said mixing arm for free radial adjustment, said burner comprising a base section and a top section, said top section being provided with a cast iron burner plate having a series of transverse orifices in parallel relation to each other, said orifices having marginal portions covered with cast surface scale, and being spaced from each other by means of transverse channels extending completely across the top surface of the burner and said burner plate presenting on its under side a series of parallel surfaces of substantially semi-circular cross-section terminating adjacent said orifices and providing passageways leading to said respective orifices of progressively decreasing width.

- A gas burner comprising a lower section formed with a marginal slot having an offset flange and an upper section adapted

to be engaged on said seat in spaced relation to said flange, a packing inserted between said upper section and said flange causing said sections to be secured together in gas-tight relation, the upper section comprising a cast iron burner plate formed with an upper surface presenting a series of transverse channels in parallel relation throughout its length and presenting a series of transverse parallel substantially semi-cylindrical surfaces on its under side, said surfaces approaching each other and terminating respectively at transverse orifices having marginal portions covered with cast surface scale, extending parallel to each other across said burner plate.

Signed by us this 14th day of May, 1928.
